ICE TRAY GRID

Arthur J. Frei and Raymond C. Davis, Dayton, Ohio,
assignors to General Motors Corporation, Detroit,
Mich., a corporation of Delaware

Application February 17, 1958, Serial No. 49,659

Term of patent 14 years

(Cl. D67—3)

Figure 1 is a perspective view of the ice tray grid showing our new design and having a grid wall actuator thereon;

Figure 2 is another perspective view of the ice tray grid taken from the end and side thereof opposite that shown in Figure 1; and

Figure 3 is an end view of the grid opposite the end thereof shown in Figure 1; and

Figure 4 is a fragmentary top plan view of an end portion of the grid showing the curvature and inclination of a transverse wall thereof.

The dominant features of the design reside in the particular transverse grid elements in association with the specific actuator lever located at one end of the longitudinal grid element.

We claim:

The ornamental design for an ice tray grid, as shown and described.
